(57) **CLAIM**

The ornamental design for a display screen with animated graphical user interface, as shown and described.

DESCRIPTION

1. Display screen with animated graphical user interface

1.1 : Front; and

1.2 : Front view in changed state 1

The outermost broken line rectangle shows the display screen, and forms no part of the claimed design. All other broken lines show portions of the graphical user interface that form no part of the claimed design.

The appearance of the animated graphical user interface transitions sequentially between reproductions 1.1 and 1.2. The process or period in which one image transitions to another forms no part of the claimed design.
